INVENTOR

Russell Games Slayter,

BY

Arthur M. Hood.

ATTORNEY

UNITED STATES PATENT OFFICE.

RUSSELL G. SLAYTER, OF LA FAYETTE, INDIANA.

OIL BURNER.

Application filed June 9, 1923. Serial No. 644,293.

To all whom it may concern:

Be it known that I, RUSSELL G. SLAYTER, a citizen of the United States, residing at La Fayette, in the county of Tippecanoe and State of Indiana, have invented a new and useful Oil Burner, of which the following is a specification.

My invention relates to improvements in oil burners and more particularly to that 10 type of burner known as gravity burners.

It is one of the objects of my invention to provide a burner which will burn the so called heavy oils and which may be cheaply constructed and readily installed and which 15 will give the greatest efficiency obtainable in this type of burner.

For the purpose of disclosing my invention I have illustrated one embodiment thereof in the accompanying drawings in 20 which,

Fig. 1 is a side elevation of the burner installed in a furnace;

Fig. 2 is a plan view of the burner;

Fig. 3 is an enlarged section on the line 25 3—3 of Fig. 2;

Fig. 4 is an enlarged section on the line 4—4 of Fig. 2;

Fig. 5 is an enlarged section on the line 5—5 of Fig. 2, and

Fig. 6 is an enlarged section on the line 20 6—6 of Fig. 1.

In the embodiment illustrated I have shown my burner used in connection with a furnace 1, the grate of which has been removed and the burner inserted in place in 35 the firepot 2 and the firepot sealed with the exception of at the point where the supply of air for the burner is led thereinto.

The burner is provided with a pan shaped 40 base 3 preferably formed of sheet metal and being cylindrical in shape. At the upper edge of the side walls of the base 3 I provide the base with an inwardly extending flange 4. This flange is adapted to support a dish shaped burner pan 5 having at 45 its outer periphery an annular shoulder 6 and provided at its center with an upwardly extending cone 7. The cone at its top is flattened and grooved, and on the surface 50 of the cone is formed a plurality of spiral ridges 8 which extend outwardly to the walls 9 of the air openings formed in the burner plate 5. The cone 7, through its center, is provided with an oil feed opening 55 10. The air openings 11 formed through the plate are provided with annular flanges

11' which position the arched air supply pipes 12. These pipes at their upper ends merge tangentially into an enlarged air chamber 13 having a bottom opening 14 60 immediately above the cone 7. The air supply pipes and air chamber are preferably formed from a single casting and I have discovered that the best results are obtained by making the area of the opening 14 equal 65 to the sum of the areas of the air supply pipes 12.

The base 3 forms an air chamber beneath the burner pan and this air chamber is supplied with air by means of a conduit flue 70 15 connected at one end with the base and arranged to extend beyond the firepot. It is provided at its outer end with a valve 16 by which the quantity of air supplied to the air chamber in the base and consequently to the burner, may be properly controlled.

Oil is supplied to the opening in the cone 7 by an oil supply pipe 17 which communicates with said opening at the bottom and which extends outwardly through the air 80 flue 15 to a point beyond the furnace wall. This pipe then takes a right angle bend and extends out through the side of the flue where it is connected with the supply pipe 18 provided with a hand controlled valve 85 19 and connected with an auxiliary supply chamber 20 provided with a float controlled valve 21. This supply chamber is connected with the main oil supply and interposed between the main oil supply and the auxiliary supply chamber is a filter 22 90 adapted to receive the oil from the main supply pipe 23 at a point near its bottom and having a chamber 24 filled with a filtering material, such for instance as 95 felted wool or the like. The connection between the filter and the auxiliary supply chamber is at the top of the filter so that the oil under a slight head is forced upwardly through the filtering material and 100 out at the top into the auxiliary supply chamber. The main oil supply pipe is provided with an automatically operated valve 25 operated by a weighted lever arm 26. This arm is engaged, in its raised position, 105 the position in which the valve is open, by a trigger arm 27 pivoted on the filter and supporting at one end an overflow receiving pan 28, which pan is mounted in a position below an overflow pipe 29. It will be noted 110 that the burner dish is so supported in the base 3 that, if for any reason, the oil should

fail to burn, or should not be wholly consumed in the dish, the accumulated oil in the dish might overflow the shoulder 6 and into the base 1 from whence it would flow 5 through to the pipe 29' into the pan 28. Any overflow from chamber 20 will pass through a pipe 20' into pan 28. As soon as the pan becomes loaded the weight of the oil therein will swing the arm 27, thereby 10 throwing the weighted arm 26 past center so that it will drop and shut off the fuel supply.

A bypass 30 is provided in the supply pipe 18, which bypass is provided with a 15 hand valve 31 and an automatic valve 32 so that in event it is desired to provide an automatic means for controlling the heat supplied by the furnace, the hand valve in the pipe 18 may be shut, thereby causing 20 the fuel to flow through the bypass 30, where it will be subjected to the control of the automatic valve 32.

A supplementary air conduit 33 extends through the flue 15 and opens to the atmosphere independently of the valve 16. This 25 conduit communicates with a supplemental air conduit 34 which extends up along the side of one of the air supply pipes 12 and passes down through the top of the air chamber 13 to a point immediately above the cone 7. At the nozzle end of this conduit 34 there is provided a cone-shaped deflector plate or nozzle plate 35, which deflects the air from the entry point of the fuel. This 30 supplemental air supply furnishes sufficient air to maintain the fuel burning when the fuel supply is cut down to the minimum and the main air supply is cut off by the closure of the valve 16. By the provision of the 35 deflector plate 35 the admission of the air immediately above the decreased fuel supply prevents the air from blowing the flame out.

The air and fuel supply to the burner are controlled by a thermostatically controlled 45 motor 36 which may be either electrically or spring operated, and is caused to operate to start the burner or stop the burner by means of a thermostat having an electrical connection with the motor and adapted to be 50 placed in the apartment, the heat of which is to be controlled. The motor is provided with an operating arm 37 adapted to be connected with a lever arm 38 on the valve 16 and also with a lever arm 39 on the automatic oil control valve. When the motor is operated to shut, or partially shut, the air control valve 16, it also operates to shut, or 55 partially shut, the fuel control valve 32. The fuel control valve is never entirely closed 60 so that even when the apparatus is in a shut-off condition, there is a small supply of oil admitted for the purpose of maintaining an ignition, or turned-down flame. When, however, the burner is in this condition, the main 65 air supply valve 16 is closed entirely and air

is supplied to maintain combustion of the oil by the supplementary or auxiliary air supply conduit 33.

In order to maintain the air supply to the burner constant under all conditions and 70 prevent fluctuation in the air supply, I provide in the draft flue of the furnace, a balanced valve 40 which will open or close, depending upon the draft conditions in the flue, thereby admitting more or less air into 75 the draft flue of the furnace and maintaining in the air supply flue 15 a constant pressure. Valve 40 is carried by a ring 41 rotatable in the neck 42 so that it may be set 80 properly irrespective of the angle of the smoke flue 43 and this neck is carried by a split thimble 44 which may be clamped around the smoke flue by bolt 45.

I claim as my invention:

1. In an oil burner, in combination, a base 85 pan, a dish shaped burner plate supported by said pan and substantially closing the top of said pan to form beneath the plate an air chamber, said plate having a centrally arranged distributor cone with an oil supply 90 opening extending therethrough, arched air tubes receiving air from the air chamber and terminating in an air chamber above said cone, which chamber opens above the cone for supplying air for the purpose of combustion, an air flue for supplying air to the chamber beneath the burner plate, an oil supply conduit for supplying oil to the burner plate, a valve capable of being completely closed for controlling the admission 95 of air to said conduit, a second valve incapable of being completely closed for controlling the admission of oil to the oil conduit, means for simultaneously operating said 100 valves and a secondary air supply conduit terminating immediately above the cone burner plate and arranged to deliver a supply of air independently of the position of the valve controlling the admission of air to the flue.

2. In an oil burner, in combination, a base pan having an air chamber formed therein, a burner plate mounted above said air chamber and having a cone shaped distributor at its center provided with an oil supply opening, a plurality of arched air tubes mounted on said burner plate and receiving air from said air chamber, said tubes terminating in an air chamber having a delivery opening 115 above the cone on the burner plate, an air flue communicating with the air chamber in said base pan, a valve for controlling the admission of air into said air chamber and a secondary air supply conduit terminating 120 immediately above the cone on the burner plate and arranged to deliver a supply of air independently of the position of the valve controlling the admission of air to the flue.

3. In an oil burner, in combination, a base 130 pan having an air supply chamber formed

therein, a burner plate mounted above said chamber and having a cone distributor on its upper side provided with a supply opening, a plurality of air supply pipes receiving air from the chamber in the base pan and terminating in an air chamber having an opening above the burner cone, an air conduit communicating with the air chamber in the base pan and supplying substantially all of the air for combustion purposes to said burner, a valve controlling the admission of air into said conduit and a secondary air supply conduit delivering air above the burner opening and receiving air independently of the main air supply conduit.

4. In an oil burner, in combination, a base pan having an air supply chamber formed therein, a burner plate mounted above said air supply opening having on its upper surface a cone distributor provided with a central vertically arranged oil supply opening, a plurality of air supply pipes receiving air from said air chamber and terminating in an air chamber opening above said distributor cone and a secondary air conduit opening immediately above the distributor cone and having a cone shaped deflector plate at the nozzle end thereof.

5. In an oil burner, in combination, a burner plate having a cone shaped distributor formed thereon and provided with a centrally arranged oil supply duct, a plurality of air supply pipes receiving air from beneath said plate and terminating in an air chamber having an opening above said distributor, a secondary air supply conduit terminating in a nozzle immediately above the distributor and having a cone shaped deflector plate at the nozzle end thereof above the oil supply opening in the distributor.

6. In an oil burner, in combination, a burner plate having a centrally arranged cone shaped distributor provided on its surface with a plurality of spirally arranged ribs diverging toward the base of the distributor, said distributor having an oil supply duct, a plurality of air supply pipes receiving air from beneath the plate and terminating in a chamber having an opening above the distributor and a secondary air supply duct terminating immediately above the distributor in a nozzle having a cone shaped deflector plate at its end.

7. In an oil burner, in combination, a base pan, a dish shaped burner plate supported by said pan and substantially closing the top of said pan to form beneath the plate an air chamber, said plate having a centrally arranged distributor cone with an oil supply opening extending therethrough, arched air tubes receiving air from the air chamber and delivering tangentially into an air chamber above said cone, which chamber opens above the cone for supplying air for

the purpose of combustion, an air flue for supplying air to the chamber beneath the burner plate, an oil supply conduit for supplying oil to the burner plate, a valve for controlling the admission of air to said conduit, a second valve for controlling the admission of oil to the oil conduit and means for simultaneously operating said valves.

8. In an oil burner, in combination, a base pan having an air chamber formed therein, a burner plate mounted above said air chamber and having a cone shaped distributor at its center provided with an oil supply opening, a plurality of arched air tubes mounted on said burner plate and receiving air from said air chamber, said tubes delivering tangentially into an air chamber having a delivery opening above the cone on the burner plate, an air flue communicating with the air chamber in said base pan, a valve for controlling the admission of air into said air chamber and a secondary air supply conduit terminating immediately above the cone on the burner plate and arranged to deliver a supply of air independently of the position of the valve controlling the admission of air to the flue.

9. In an oil burner, in combination, a base pan having an air chamber formed therein, a burner plate above said air chamber having a cone shaped distributor at its center provided with a fuel inlet, a plurality of arched air tubes receiving air from the chamber in the base pan and delivering tangentially into an air chamber opening above the cone, a valve controlled air supply flue communicating with the air chamber in the base pan, an oil conduit extending to said fuel opening in the burner plate and a float controlled valve arranged in said oil conduit.

10. In an oil burner, in combination, a base pan having an air chamber formed therein, a burner plate mounted above said air chamber and having a cone distributor provided with an oil supply opening, a plurality of air supply pipes receiving air from said air chamber and delivering tangentially into an air chamber opening above said cone, a valve controlled flue communicating with the air chamber in the base pan, an oil supply conduit extending to the oil supply opening in the cone, a float controlled valve arranged in said oil supply conduit and a filter interposed between the fuel oil supply and said valve.

11. In an oil burner, in combination, a base pan having an air supply chamber formed therein, a burner plate mounted above said chamber and having a cone distributor on its upper side provided with a supply opening, a plurality of air supply pipes receiving air from the chamber in the base pan and delivering tangentially into an air chamber having an opening above the burner cone, an air conduit communicating

with the air chamber in the base pan and supplying substantially all of the air for combustion purposes to said burner, a valve controlling the admission of air into said conduit and a secondary air supply conduit delivering air above the burner opening and receiving air independently of the main air supply conduit.

12. In an oil burner, in combination, a base pan having an air supply chamber formed therein, a burner plate mounted above said air supply opening having on its upper surface a cone distributor provided with a central vertically arranged oil supply opening, a plurality of air supply pipes receiving air from said air chamber and delivering tangentially into an air chamber opening above said distributor cone and a secondary air conduit opening immediately above the distributor cone and having a cone shaped deflector plate at the nozzle end thereof.

13. In an oil burner, in combination, a burner plate having a cone shaped distributor formed thereon and provided with a centrally arranged oil supply duct, a plurality of air supply pipes receiving air from beneath said plate and delivering tangen-

tially into an air chamber having an opening above said distributor, a secondary air supply conduit terminating in a nozzle immediately above the distributor and having a cone shaped deflector plate at the nozzle end thereof above the oil supply opening in the distributor.

14. In an oil burner, in combination, a burner plate having a centrally arranged cone shaped distributor provided on its surface with a plurality of spirally arranged ribs diverging toward the base of the distributor, said distributor having an oil supply duct, a plurality of air supply pipes receiving air from beneath the plate and delivering tangentially into a chamber having an opening above the distributor and a secondary air supply duct terminating immediately above the distributor in a nozzle having a cone shaped deflector plate at its end.

In witness whereof, I RUSSELL G. SLAYTER have hereunto set my hand at Lafayette, Indiana, this fifth day of June, A. D. one thousand nine hundred and twenty three.

RUSSELL G. SLAYTER.
